(74) Attorney, Agent, or Firm—Fish & Richardson P.C.

(57) **CLAIM**

The ornamental design for a shoe sole, as shown and described.

DESCRIPTION

FIG. 1 is a perspective view of a shoe sole showing my new design, the small diamond pattern being understood to cover the outer surface of the shoe sole.

FIG. 2 illustrates a first side view of the shoe sole design of FIG. 1;

FIG. 3 illustrates an opposite side view of the shoe design of FIG. 1;

FIG. 4 illustrates a front view of the shoe sole design of FIG. 1;

FIG. 5 illustrates a back view of the shoe sole design of FIG. 1;

FIG. 6 illustrates a bottom view of the shoe sole design of FIG. 1; and,

FIG. 7 illustrates a top view of the shoe sole design of FIG. 1.

The broken lines shown in FIGS. 4 and 7 are understood to represent stitching.
